STOCKING

Henry T. Bryan, Chattanooga, Tenn.

Application January 7, 1953, Serial No. 23,064

Term of patent 7 years

(Cl. D47—7)

To all whom it may concern:

Be it known that I, Henry T. Bryan, a citizen of the United States of America, residing at city of Chattanooga, county of Hamilton, State of Tennessee, have invented a new, original, and ornamental Design for a Stocking, of which the following is a specification, reference being had to the accompanying drawing, forming part thereof.

I claim:

The ornamental design for a stocking, as shown.

HENRY T. BRYAN.
